UNITED STATES PATENT OFFICE.

MOSES C. NIXON, OF CHICAGO, ILLINOIS.

BALING-PRESS.

No. 835,632.

Specification of Letters Patent.

Patented Nov. 13, 1906.

Application filed August 23, 1905. Serial No. 275,435.

To all whom it may concern.

Be it known that I, MOSES C. NIXON, a citizen of the United States of America, and a resident of Chicago, in the county of Cook and State of Illinois, have invented certain new and useful Improvements in Baling-Presses, of which the following is a specification.

This invention relates to improvements in baling-presses in which condensing mechanism is employed in conjunction with the baling-chamber; and the object of my improvement is to provide a simple and effective mechanism for operating the condenser.

The invention consists in a link or toggle mechanism to operate a condenser. It may be applied to different forms of condensers and driven by any suitable power or connection therewith and its form of construction varied without departing from the spirit of my invention.

The object of this invention is accomplished, preferably, by the construction illustrated in the accompanying drawings, in which—

Figure 1 is a side elevation of a baling-press with a condensing mechanism in connection therewith, a part of the baling-chamber being shown cut away; and Fig. 2 is a plan view of Fig. 1, showing a part of the feed-platform cut away and the feeder omitted.

Similar numerals of reference indicate corresponding parts in both views, and, referring now to the same, 1 is the frame of a baling-press, 2 is the driving mechanism, and 3 is the plunger, which is reciprocated horizontally in the baling-chamber 4 by means of the driving mechanism which has actuating connection therewith.

5 is the feeder, which operates in the usual manner and is actuated by means of the driving mechanism above mentioned.

A feed-platform 6 is suitably supported above the frame 1 and has a feed-opening 7 therein. At one end of the feed-opening is an upwardly-extending sill 8, at each end of which is hinged a condensing-wing 9. The wings 9 are rigidly fixed, respectively, upon vertical shafts 10, which are adapted to turn in the corresponding ends of the sill 8. The lower ends of the shafts 10 extend down through the feed-platform 6, and each has mounted upon its extending end a crank 11.

To the under side of the feed-platform, 55 upon either side of the frame 1, is pivoted a triangular link 12, as indicated at 13. Each of said links is connected with the corresponding cranks 11, respectively, by means of bars 14, and said links have also connections at their longest ends, (indicated at 15,) respectively, with the corresponding ends of a cross-piece 16 by means of arms 17. The cross-bar 16 is rigidly fixed to the plunger 3, and it will appear that as the plunger is actuated the links 12 will become moved accordingly and the condenser-wings will in turn be operated thereby.

The two extreme positions of the condenser-wings, links, and the connecting-bars 70 and arms are indicated in Fig. 2 of the drawings. The full lines and part of the dotted lines indicate one extreme, and the other dotted lines indicate the opposite extreme.

It will be noted that when the plunger is 75 reversed from one stroke to the other the relative positions of the links and the arms 17 and bars 14 in connection therewith are such as to afford gradually-increasing movement to the condensing-wings at the commencement of either their inward or outward swing and a gradually-decreasing movement at the end of their inward or outward swing.

In the operation of this invention the plunger and feeder are set in motion by means of 85 the driving mechanism, and because of the connection of the links with the driving mechanism and the condenser-wings the latter will be actuated. When the plunger is farthest in the baling-chamber, the condenser-wings 90 are distended and the feeder is uppermost, and when the plunger is at its opposite extreme position the condenser-wings are closed and the feeder is in its lowermost position, and during the movement of the condenser-wings from one extreme position to 95 the other the motion thereof is gradual and unattended by jerks, the even motion being due to the peculiar relation of the links and their pivotal connections with the condenser-wings and driving mechanism.

As will be understood, I do not use the expression "link mechanism" or other expressions in which the word "link" is employed in any strict or technical sense. On the contrary, I use them as meaning and including "toggle" as well as "link," "links," or "link mechanism."

Having described my invention, what I claim as new, and desire to secure by Letters Patent, is—

1. In apparatus of the class described, a baling-press having driving and condensing mechanism in connection therewith; a pivotally-supported triangular link; an arm having pivotal connections at its ends respectively with the link and driving mechanism to actuate the latter. 5
2. In apparatus of the class described, in combination with a baling-press having driving and condensing mechanism, two triangular links oppositely disposed and each having pivotal support at one corner thereof; two arms, each having pivotal connections at its ends respectively with a corner of the corresponding link and the driving mechanism; and two connecting-bars, each having connections at its ends respectively with the other corner of the corresponding link and the condensing mechanism. 15
3. In apparatus of the class described, in combination with a baling-press having driving and condensing mechanism, two triangular links oppositely disposed and each having pivotal support at one of its corners, the other two corners thereof having connections respectively with the driving and condensing mechanism by means of a pivoted arm and bar. 25
4. In apparatus of the class described, a baling-press having a reciprocating plunger; condensing mechanism in connection with the baling-press, a triangular link having pivotal support at one of its corners and connections at its other corners respectively with the plunger and condensing mechanism by means of a pivoted arm and bar. 35
5. In apparatus of the class described, a baling-press having a reciprocating plunger; condensing mechanism in connection with the baling-press having two oppositely-disposed swinging condensing-wings; two triangular links, each pivotally supported at one of its corners; arms having pivotal connections respectively with one of the other corners of the corresponding links and the plunger; and connecting-bars having connections respectively with the remaining corners of the corresponding links and the corresponding wings of the condensing mechanism. 45
6. In apparatus of the class described, in combination with a baling-press having a reciprocating plunger and oppositely disposed swinging condensing-wings, two triangular links oppositely disposed and each having pivotal support at one of its corners and respective connection at its other two corners with the plunger and the corresponding condensing-wing. 55
7. In apparatus of the class described, in combination with a baling-press having driving mechanism and oppositely disposed swinging condensing-wings, two triangular 65
- links oppositely disposed and each having pivotal support at one of its corners and respective connections at its other two corners with the driving mechanism and the corresponding condensing mechanism. 70
8. In apparatus of the class described, in combination with a baling-press having driving and condensing mechanism, two triangular links oppositely disposed and each having pivotal support at one of its corners and respective connections at its other two corners with the driving and condensing mechanism to actuate the latter. 75
9. In apparatus of the class described, in combination with a baling-press having driving and condensing mechanism, a triangular link having pivotal support at one of its corners and connections at its other two corners respectively with the driving and condensing mechanism. 80
10. In apparatus of the class described, a baling-press having driving and condensing mechanism; and a swinging link having pivotal support, the said driving and condensing mechanism each having an independent actuating connection with said link. 85
11. In apparatus of the class described, a baling-press having driving mechanism and condensing-wings; two pivotally-supported links oppositely disposed, each having actuating relation with said driving mechanism; and means connecting the respective links with the corresponding condensing-wings to actuate the latter. 95
12. In a baling-press, a baling-chamber in connection with a condenser and a driving mechanism; and a pivotally-supported link or links having connections with the driving mechanism and condenser to transmit motion from the former to the latter. 100
13. In a baling-press, a reciprocating plunger; a condenser; and a pivotally-supported link or links having connections with said plunger and condenser to transmit motion from the former to the latter. 105
14. In a baling-press, a baling-chamber; a driving mechanism; a condenser; and a link mechanism suitably connected with said driving mechanism and condenser to cause the latter to open and close. 110
15. In a baling-press, a driving mechanism; a condenser; and a link mechanism suitably connected with the driving mechanism and condenser to cause the latter to open and close. 115
16. In a baling-press, a driving mechanism; a reciprocating plunger; a condenser; and a link mechanism suitably connected with the plunger and condenser to cause the latter to open and close. 120
17. In a baling-press having driving mechanism and a condenser, a link mechanism having connections with the driving mechan- 125

ism and condenser to be driven by the former and to actuate the latter in a horizontal plane.

18. In a baling-press having a baling-chamber and driving mechanism; a condenser; and one or more pivotally-supported links having connections with the driving mechanism and condenser to be driven by the former and to actuate the latter in a horizontal plane.

19. In a baling-press having a reciprocating plunger; a condenser; and one or more pivotally-supported links having connection with said plunger and condenser to be driven by the former and to actuate the latter in a horizontal plane.

20. In a baling-press having driving mechanism and a condenser, a link mechanism having connections with the driving mechanism and condenser to be driven by the former and to cause the latter to open and close.

21. In a baling-press having a reciprocating plunger; a condenser; and link mechanism having connections with said plunger and condenser to be driven by the former and to actuate the latter.

22. In a baling-press having driving mechanism and condensing-wings; two pivotally-supported links oppositely disposed each having connection with said driving mechanism to be actuated thereby; and means connecting said links respectively with the corresponding condensing-wings to operate the same in a horizontal plane. 30

23. In a baling-press having driving mechanism and condensing-wings, a link mechanism connected with the driving mechanism to be actuated thereby; and means connecting the link or toggle mechanism and condensing-wings to actuate the latter. 35 40

24. In a baling-press having a baling-chamber, a driving mechanism and a condenser; and a link mechanism having connections with the driving mechanism and condenser to be driven by the former and to 45 actuate the latter in a horizontal plane.

In testimony whereof I affix my signature in presence of two witnesses.

MOSES C. NIXON.
